UNITED STATES PATENT OFFICE.

HERBERT W. COLLINS, OF GRAND FORKS, BRITISH COLUMBIA, CANADA.

GAME APPARATUS.

1,176,033.

Specification of Letters Patent. Patented Mar. 21, 1916.

Application filed April 20, 1915. Serial No. 22,675.

To all whom it may concern:

Be it known that I, HERBERT W. COLLINS, a subject of the King of Great Britain, residing at Grand Forks, in the Province of British Columbia and Dominion of Canada, have invented new and useful Improvements in Game Apparatus, of which the following is a specification.

This invention is an improved game apparatus for playing a game which we call "empire".

The object of the invention is to provide an improved game apparatus which may be used by varying number of players and 15 in connection with cards, the flags of nations and a ball or marble for playing a highly entertaining and interesting game which is calculated to appeal to patriotic sentiment.

20 The invention consists in the construction, combination and arrangement of devices hereinafter described and claimed.

Figure 1 is a plan for a game apparatus constructed in accordance with my invention. Fig. 2 is a sectional view of the same on the plane indicated by the line *a—a* of Fig. 1. Fig. 3 is a similar view on the plane indicated by the line *b—b* of Fig. 1. Fig. 4 is a view showing the flags used in connection with the game. Fig. 5 is a view showing the cards used in connection with the game.

In accordance with my invention I provide a game board 1 which is here shown as 35 polygonal and is provided at its outer side with a guard wall 2. The board is divided into a series of segmental fields 3 by means of radial walls 4. Each wall 4 is provided with a runway 5 on its upper side that inclines downwardly and outwardly and discharges at its lower, outer end, on a small raised block 6. Said blocks 6 are arranged in the angles between the walls 4 and 2 and the said blocks are segmental in form and 40 each is provided with numbered holes or pockets 7 and also with a stop 8, the holes or pockets being near the ends and the stop being at the center of the block. Each block also has a flange wall 9 on its front side.

50 In the center of the board is a tower 10 the base of which is detachably connected to the board. The tower is polygonal in plan, with its angles presented to the inner ends of the runways 5 and its faces presented to 55 the fields 3. A tube 11 is vertically arranged in the upper portion of the tower and pro-

jects upwardly through the center of the roof thereof. In the base of the tower is a cone 12 on the apex of which is a ball 13. The cone is provided with inclined alternating ways 14, 15 which respectively communicate at their lower ends with openings 16, 17 said openings 16 being in the angles of the tower and said opening 17 being in the faces thereof. The openings are slightly 60 above the inner ends of the runways 5 and the openings 17 are above the inner portions of the fields 3. The fields form inclined planes, their inner ends being higher than their outer portions.

70 Each field is provided at its outer side with one or more pockets 18; with stops 19 near its outer corners, a nearly centrally located stop 20 which has pockets 21, 22, and is further provided at its sides near its 75 inner end with stops 23. On each field near the opening 17 is a fender stud 24. The fields are also provided with figures, representing soldiers, cannon, ships, or the like, and some of the figures are provided with 80 flags. The figures are all removable and may be secured in place in the fields by placing them in recesses 25 with which the fields are provided. One of the fields will be inscribed to indicate a nation, "Our Empire". Another will be inscribed to indicate the chief executive officer of the nation such as "Our President." Another will be inscribed "Our Army", another "Our 85 Navy", another "Our Flag" and so on and 90 appropriate figures will be placed in the fields.

95 In connection with the game board a pack of cards numbered from one up will be employed and also small flags of the various nations. The persons playing draw each a card from the pack and the one who holds the highest numbered card selects one of the flags indicating the nation his side is to represent. The holder of the next highest card does the like and so on, each of the players providing himself with a flag. The game is played by dropping a ball or marble 27 in the tube at the upper end of the tower. The ball passes out of the tower 100 either through one of the openings 16 or one of the openings 17, as chance may direct. A ball dropping from one of the openings 16 will fall on one of the blocks 5 and be directed thereby to one of the blocks 110 6 and if it lodges on one of the pockets on said block will score for the player accord-

ing to the value of said pocket. These values will be inscribed, in practice in all of the pockets so that they will be known by all the players. If a ball drops through one of the openings 17 it will fall on one of the fields and will strike and be deflected by the fender stud. Owing to the inclination of the field the ball will roll thereon and if it lodges in one of the pockets will score accordingly. After a predetermined number of plays by each player, the person scoring the highest number will win, or if a number has been selected, the first person to score up to that number will win. The figures in practice are artistically constructed and appropriately painted and ornamented and impart a lively and pleasing appearance on the game board.

Having thus described my invention I claim:—

Copies of this patent may be obtained for five cents each, by addressing the "Commissioner of Patents, Washington, D. C."

A game apparatus of the class described comprising a board having inclined fields each provided with stops and pockets, runways elevated above and dividing the fields, elevated blocks at the outer ends of the runways and provided with pockets, and a tower in the center of the board and at the intersection of the runways and provided with an opening at its top, and with a cone in its base, said cone having inclined passages leading some to the fields and some to the runways and adapted to direct a ball dropped into the tower either to one of the runways or one of the fields. 25 30 35

In testimony whereof I affix my signature in presence of two witnesses.

HERBERT W. COLLINS.
